[57] CLAIM

The ornamental design for a body massaging device, as shown and described.

DESCRIPTION

FIG. 1 is a perspective view of a body massaging device, showing my new design;

FIG. 2 is a top plan view thereof.

FIG. 3 is a front elevational view thereof, the rear elevational view being a mirror image thereof;

FIG. 4 is a left side elevational view thereof, the right side elevational view being a mirror image thereof; and,

FIG. 5 is a bottom plan view thereof.
